UNITED STATES PATENT OFFICE

ALBERT H. TINNERMAN, OF CLEVELAND, OHIO

DESIGN FOR A STOVE PANEL ASSEMBLY

Application filed October 30, 1931. Serial No. 41,583. Term of patent 7 years.

To all whom it may concern:

Be it known that I, ALBERT H. TINNERMAN, a citizen of the United States, residing at Cleveland, in the county of Cuyahoga and State of Ohio, have invented a new, original, and ornamental Design for a Stove Panel Assembly, of which the following is a specification, reference being had to the accompanying drawing, forming a part thereof.

In the drawing, Fig. 1 is a front elevation

of a stove panel assembly, embodying my invention, and Fig. 2 is an enlarged side elevation thereof. The dominant feature of the design is the compact superimposed grouping of the burner control handles.

I claim:

The ornamental design for a stove panel assembly, as shown and described.

ALBERT H. TINNERMAN.
